UNITED STATES PATENT OFFICE.

JOHN POOLE AND THOMAS J. PATTIN, OF HARMAR, OHIO.

IMPROVEMENT IN CLAMPING AND NAILING WASH-BOARDS.

Specification forming part of Letters Patent No. 38,411, dated May 5, 1863.

To all whom it may concern:

Be it known that we, JOHN POOLE and THOMAS J. PATTIN, of the town of Harmar, in the county of Washington and State of Ohio, have invented a new and useful machine for clamping and nailing in the manufacture of zinc wash-boards; and we do hereby declare that the following is a full and exact description of the same, reference being had to the annexed drawings, making a part of this specification, in which—

Figure 1 is a perspective view of the whole machine. Fig. 2 is a view of the shaft. Fig. 3 is a view of the clamps (sliding.) Fig. 4 is a view of the clamp, showing the flange. Fig. 5 is a transverse view of the machine.

Our clamping and nailing machine is of simple construction and easily understood, it being placed simply on a stout shaft, A, Figs. 1 and 2, upon two standards or posts, B B, Fig. 1, fastened to the floor C, Fig. 1. This shaft A has two little cams, D D, Fig. 2, hereinafter more fully described. The clamps E E, Fig. 1, are made of heavy boiler-iron, fourteen inches wide and sixteen inches long. Two inches of one end of each piece is turned at right angles upward to form a clamp. These plates are put together with little bolts, (not shown,) fastened in the upper plate and passing through a slot in the lower to allow them to move. There is a portion, F F, Fig. 3, taken out of the center of each side of the lower plate, so as to move past the bearings of the shaft that is fastened to the upper plate. To the lower plate is fastened firmly straps or yokes H H, into which small cams work on the said shaft A. Attached to the upper plate is a piece of boiler-iron, I, Fig. 1, eleven inches wide and twenty-four inches long inside the turns on each end. This piece is for holding the side pieces of the wash-board to their places lengthwise while clamping and nailing. On the end of the shaft A, at the right hand of the operator, is a lever, K, fastened. When this lever is from the operator, the cams D D on the shaft A moves the lower plates outward, widening the space between the flanges or clamps

E E on the outer ends, and when the lever is turned toward the operator the plates or clamps are drawn back and the space between the clamps contracted. In front and between the two standards or posts, B B, stands a resting-post, L, on which the front side of the clamps rest while placing in the material and clamping. The clamps are turned with the shaft on the standards (without effecting the clamps) from the operator till the clamps stand perpendicular, presenting the edge in the right position to nail the wash-board, which is done through holes in the flanges for that purpose. The said resting-post L is made elastic, so that the clamps can be turned down the other way past it for nailing the other side.

The operation of our clamping and nailing machine is very plain and simple. The two side pieces of the wash-board are laid on the clamps against the flanges E E, the back piece is laid between them in the center lengthwise, the lever is drawn over by the operator, bringing the cams D D in contact with the yokes H H. The clamps are drawn powerfully together and the zinc plates pressed hard against the back board. The clamp is turned first upon one edge, then upon the other, and nailed through the holes represented in Fig 1. The clamp is then loosed and turned to its original place on the resting-post, the lever being thrown over from the operator, relieving the board for another operation.

After having thus fully described our clamping and nailing machine for wash-boards, what we claim as new, and desire to secure by Letters Patent, is—

The sliding clamps E E, standards or posts B B, with the lever L and cams D D, in the manner and for the purposes set forth.

This specification signed and witnessed this 12th day of December, A. D. 1862.

JOHN POOLE.
T. J. PATTIN.
